UNITED STATES PATENT OFFICE.

PHILIPPE WOLF, OF PARIS, FRANCE.

WASHING APPARATUS FOR COALS.

Application filed June 28, 1926, Serial No. 119,016, and in France July 3, 1925.

The invention relates to improvements in coal washing apparatus of the kind in which a mechanically actuated piston produces pulsation of the water contained within the 5 washing vat.

It is already known to use a mechanical pistonning device in which the separation of the products is effected by means of a stream of water pulsating through the bed of materials to be washed, the evacuation of the slates or other heavy substances being automatically regulated according to the thickness of the bed.

The purpose of the improvements which 15 form the subject matter of this invention consists in the construction of a simple, strong and effective apparatus by means of which the evacuation of the slates or of other heavy substances is automatically regulated according to the amount or the thickness 20 of the layer of slates to be evacuated.

Another feature of the invention consists in the fact that the apparatus is not provided with any mechanical member immersed in 25 the products to be evacuated.

The modifications are represented by way of example on the accompanying drawing.

Fig. 1 shows in longitudinal section the entire mounting of the apparatus on a washing vat with mechanical pulsations, such as 30 are normally employed for washing products larger than 10 millimeters.

Fig. 2 is a plan view of this vat.

Fig. 3 shows a longitudinal section of 35 the apparatus along the line 3—3 in Fig. 2.

Fig. 4 is a sectional elevation taken on a plane at right angles to the plane of Fig. 3.

Fig. 5 represents a plan of the apparatus.

Fig. 6 is a sectional view taken on the 40 line 6—6 of Fig. 5.

Fig. 7 is a cross section of the valve along the line 7—7 in Fig. 6.

The pistonning or pulsation is produced by a piston 1 operated by eccentrics or any other 45 mechanism customarily employed.

The material to be washed, fed by a conduit 2, is separated into a layer of slates S and a bed of coals C, the coals passing away above a sill 3 and the slates being evacuated 50 through the slate-evacuating compartment 4. This latter compartment is extended at its upper part by a compression compartment 5 which communicates by piping 6 with cylinder 7 of the apparatus for automatically 55 regulating the evacuation of the slates. The piping 6 communicates, by means of a rec-

tangular opening 8, with the interior of the cylinder 7 which opens into the atmosphere. In this cylinder a valve 9, rigidly connected to a chain wheel 10, can turn.

Two rods 11 and 12 are connected by two chains 13, 14 which move around the wheels 10 and 15. The latter wheel can be adjusted in respect to its height by means of threaded rods 16.

The rod 11 carries an adjustable stop 17 which can be raised by a member 18 fixed on a rod 19 rigid with the float 20. This float follows the oscillating movement which is caused by the water in the tube 21, which 70 communicates with the atmosphere by means of an opening 22 under the influence of the pistonning produced by the piston 1.

At each termination of the upward stroke the member 18 contacts with the stop 17 and 75 pushes it to the end of the stroke. The rod 19 being guided in bearings 23 and 24, the float 20 does not rub against the tube 21, it simply floats upon the liquid contained in this tube.

The displacement of the stop 17 upwardly in the direction of the arrow H causes the wheel or pinion 10 and the valve 9 to turn in the direction of the arrow O; this movement tends to increase the size of the communicating opening between the tube 6 and the atmosphere.

On the rod 26 carrying the valve 9 and pinion 10 is keyed a disc 27 which can slide on the rod 26. A spring 28, adjusted by 90 means of a nut 29 that can be displaced along a threaded sleeve keyed to the rod 26, applies the disc 27 against a disc 31 rigid with a worm wheel 32 loose on the shaft 26 and held in place by a ring 33.

The wheel 32 is turned in the direction of arrow F by a worm 34 controlled by means of a suitable transmission from a pulley 35. It will be seen that the wheel 32 turns, in a continuous manner by means of friction between the plates 27 and 31, the valve 9 in the direction of the arrow F which tends to close the communication between the chamber 5 and the atmosphere.

During this time the stop 17 descends in 105 the direction of the arrow G, but at the termination of the upward movement of the float 20 the piece 18 pushes afresh the stop 17 upwardly in the direction of the arrow H which determines the displacement of the 110 valve 9 in the direction of the arrow O, the disc 27 sliding upon the disc 31.

The speed of the movement of the wheel 32 is such that between the two terminations of the upward stroke the stop 17 only descends a few millimeters. In this way it will be always in a position in the vicinity of that determined by the upward position attained by the piece 18, that is to say by the float 20.

The volume of water delivered at each pulsation by the piston 1 under the washing bed raises this latter and rises in the tube 21, so much the higher as the washing bed is heavier.

If the quantity of slates arriving in the washing apparatus exceeds the mean value, the bed of slates S tends to increase in thickness. If the bed of slates would attain its maximum thickness, the pulsation would be a maximum in the tube 21 and the stop 17 would assume its highest position, which corresponds to the maximum opening of the valve line.

The air contained in the compression chamber 5 should communicate with the atmosphere by the large open orifice of the regulating apparatus, and the bank formed by the bed of slates and limited by the sills 36 and 37 would be raised at each stroke of the piston and drawn into the slate-evacuating chamber 4, from which the slates are evacuated by piping 38. These flow out and their level tends to lower itself in the washing bed.

If the thickness of the slates bed diminishes, the pulsation diminishes correspondingly in tube 21. The valve, which is actuated by the action of the worm wheel 32 in the direction of the arrow F and which is no longer returned in the direction of the arrow O by the action of the piece 18 diminishes progressively the communication between the compression chamber 5 and the atmosphere, until it closes it completely, which checks almost totally the evacuation of the slates, because the chamber 5 being closed the air which it contains cannot escape, and prevents the water rising in this chamber under the stroke of the piston which suppresses entirely the flow between the sills 36 and 37 and arrests the evacuation of the slates which statically cannot escape.

Between the two extreme positions determining the maximum evacuation of the slates

or the complete stoppage of this evacuation, each position of the valve 9 corresponds to a determined or calculated evacuation of the slates, which evacuation increases at the same time as the opening of the valve 9 increases.

As soon as the thickness of the bed of slates tends to depart from the mean value representing the best regulation, the apparatus enters into action and tends to restore to its best value the thickness of the bed of slates.

The valve 9 is simply mounted with slight friction on the end of the rod 26 which carries a feather. It is held in place by means of a screw 39. To clean the apparatus it is sufficient to release this screw and to withdraw the valve 9.

The pulsation, instead of being determined by a mechanical pistonning, can be effected by water under pressure.

What I claim is:

1. In an apparatus for washing coals, in combination, a perforated bed on which the materials to be washed are disposed in layers with the lightest materials at the top, a piston device for intermittently forcing water through said bed and the materials thereon, a chamber communicating with the bed through which the heavier materials are evacuated, a float responsive to the pulsations of water through said materials, a valve controlling communication of said chamber with the atmosphere and means operated by said float for governing said valve.

2. In an apparatus for washing coals, in combination, a perforated bed on which the materials to be washed are disposed in layers with the lightest materials at the top, a piston device for intermittently forcing water through said bed and the materials thereon, a chamber communicating with the bed through which the heavier materials are evacuated, a float responsive to the pulsations of water through said materials, a valve controlling communication of said chamber with the atmosphere, continuously moving means tending to move said valve towards closed position, and means operated by said float for opening the valve to an extent corresponding to the extent of movement of said float.

In testimony whereof I affix my signature.
PHILIPPE WOLF.
